No. 878,038.

PATENTED FEB. 4, 1908.

F. W. BLECKLEY.
WAGON BOLSTER.

APPLICATION FILED DEC. 15, 1906.

UNITED STATES PATENT OFFICE.

FREDERICK W. BLECKLEY, OF HAZLETON, PENNSYLVANIA, ASSIGNOR TO PRESSED STEEL WAGON BOLSTER CO., OF HAZLETON, PENNSYLVANIA, A CORPORATION OF PENNSYLVANIA.

WAGON-BOLSTER.

No. 878,038.

Specification of Letters Patent.

Patented Feb. 4, 1908.

Application filed December 15, 1906. Serial No. 348,010.

To all whom it may concern:

Be it known that I, FREDERICK W. BLECKLEY, citizen of the United States, residing at Hazleton, in the county of Luzerne and State 5 of Pennsylvania, have invented certain new and useful Improvements in Wagon-Bolsters, of which the following is a specification.

This invention relates to bolsters for vehicles of the type comprising upper and 10 lower members and interposed springs, and consists of the novel features, details of construction and combinations of parts which hereinafter will be more particularly set forth, illustrated and finally claimed.

15 In the accompanying drawings forming a part of the specification, Figure 1 is a front view of a bolster embodying the invention, an end portion being in longitudinal section, or broken away, to show more clearly the 20 relative arrangement of the coöperating elements. Fig. 2 is a detail perspective view of the upper member, or body supporting bar, the parts being separated. Fig. 3 is a detail perspective view of the lower member, or 25 bolster proper. Fig. 4 is a detail perspective view of a portion of the bolster showing the strut bracing the sides thereof and receiving the head of the bolt by means of which the bolster is connected to the hounds, or other 30 part of the running gear. Fig. 5 is a cross section on the line $x-x$ of Fig. 1. Fig. 6 is a horizontal section on the line $y-y$ of Fig. 1. Fig. 7 is a modified form of the upper member of the bolster.

35 Corresponding and like parts are referred to in the following description and indicated in all the views of the drawings by the same reference characters.

The bolster comprises members 1 and 2, 40 the former constituting the upper member and designated as the body supporting bar, whereas the latter is the lower member, or bolster proper, both members being constructed of channel iron and arranged so as 45 to inclose a space within which is arranged the spring means adapted to press the members apart and sustain the load. The side flanges of the upper member 1 are spaced apart a distance to embrace the side flanges 50 of the lower member 2, thereby serving in a great measure to prevent water, dust, or the like, from entering the bolster from above.

Vertical slots 3 are formed in the side pieces of the member 1 and receive bolts, or

fastenings 4', which pass through openings 55 in the side pieces of the member 2, thereby preventing longitudinal displacement of the upper member and directing the same in its vertical movement.

The members 1 and 2 may be cast, or may 60 be formed from metal plates of suitable gage, said plates having longitudinal edge portions bent to form the side pieces, or flanges, which inclose the space receiving the 65 springs 5.

The upper member, or body supporting bar, of the bolster comprises a cap piece 6, a board 7 and a wear-plate 8, the several parts being placed one upon the other in the order named. The cap piece 6 is of metal 70 and has its extremities provided with the slots 9 designed to receive the standards 11. Similar slots 14 are formed in the wear plate 8, the sides of the slots being turned upwardly as indicated at 10. 75

The board 7 consists of a plank or slab of wood and reinforces the cap piece and is provided at each end with parallel kerfs 12 of a length corresponding to the slots 9 and adapted to receive the vertical flanges 10. 80 The intermediate portion 13, separated by the kerfs 12 is adapted to have a portion cut therefrom to admit of the standards entering the slots 9, the length of the portion to be cut from the outer end of the parts 13 being determined by the distance between the stakes 11 when adjusted to receive the bed of vehicle body. The slot, or opening, formed by cutting away a part of the portion 13 is reinforced at its sides, or edges, by the flanges 10 90 which sustain the wear incident to the vertical play of the upper member of the bolster. The wear plate 8 overlaps the board 7 and has a slot 14 extended inward from each end corresponding to the respective slots 9. The 95 several parts 6, 7 and 8 of the upper member, or body supporting bar, are connected by suitable fastenings such as rivets, or bolts. For pressing apart the upper and lower members of the bolster, any type of spring 100 may be interposed between them and inasmuch as coil springs are generally employed the same are illustrated and in order to retain such springs in place, guides 15 are provided and secured at their lower ends to the 105 horizontal portion of the member 2.

Each of the guides 15 consists of a frame formed by bending a bar upon itself into the

form substantially as shown, and attaching said frame to the member 2, the width of the frame being such as to fit within the coil spring and the height being less than the 5 depth of the side pieces, or flanges, of the member 2 so as not to interfere with the vertical play of the upper member 1.

The bolster is designed to be secured to the hounds 16, or other convenient portion of the 10 running gear, by means of bolts 17, the same being passed through openings in the hounds, or other part of the running gear and in the horizontal portion of the member 2. To admit of comparatively small bolts being 15 advantageously used, and to prevent turning of the same when tightening or loosening the clamp nuts thereof, strut pieces 18 are placed within the lower portion of the bolster. The strut pieces 18 are short lengths of channel 20 iron which correspond to the distance between the side pieces, or flanges, of the lower member 2, the space between the wings or flanges of the strut pieces corresponding to the width of the bolt heads so as to prevent 25 turning thereof when tightening or loosening the nuts coöperating therewith. The flanges of the strut pieces touch the inner faces of the side pieces or flanges on the lower member 2 and serve in a measure to brace the same, 30 and which flanges in turn, prevent turning of the strut pieces.

The stakes, or standards, 11 are provided at their lower ends with sockets 19 which inclose the ends of the bolster and give a finished 35 appearance thereto and exclude the entrance of foreign matter and prevent any one from introducing a block, stone, or other object into the bolster to prevent effective operation of the springs.

40 The stakes 11 are adjustable upon the ends of the bolster to admit of the distance between them being varied to accommodate beds and bodies of different widths. Longitudinal slots 20 are formed in the side pieces, 45 or flanges, of the lower member 2 to receive the bolts 21 by means of which the stakes are secured to the bolster in an adjusted position. Inasmuch as the terminal portions of the side pieces, or flanges, of the upper 50 member overlap the sides of the sockets 19, said terminal portions are outwardly deflected a distance to embrace opposite sides of the sockets 19 this being shown most clearly in Fig. 6.

55 The members of the bolster may be rolled, cast, pressed or constructed in any manner, and as shown in Fig. 7, the flanges 10 along the sides of the slot 14 may extend downward instead of upward and in some instances, the cap piece 6 and the board 7 may be entirely dispensed with. If the board 7 be employed, it may be placed either on top of the horizontal portion of the upper member, or beneath the same. When the board 60 65 is located within the upper member, the

wear plate 6 may be dispensed with, since the upper member will sustain the wear and strain.

The guides 15 for the springs 5 may be shifted to any position so as not to interfere 70 with the bolts 17 employed for connecting the bolster to the hounds, or other part of the running gear.

Having thus described the invention, what is claimed as new is:

1. In a wagon bolster, the combination of a lower member, stakes mounted thereon, and an upper member movable with respect to the lower member and comprising a section having slots formed therein to receive 80 the stakes, the sides of the slots carrying outstanding flanges, and a second section mounted upon the first mentioned section and formed with slots receiving the before mentioned outstanding flanges. 85

2. In a wagon bolster, the combination of a lower member, standards adjustable thereon and an upper member, the latter comprising a metal cap piece having slots in its ends and flanges at the edges of the slots, and a 90 board secured to the cap piece and having kerfs to receive the said flanges, the outer parts of the boards separated by corresponding kerfs being adapted to be cut away to receive the standards. 95

3. In a bolster for vehicles, the combination of companion members, one of said members adapted to have stakes adjustably fitted thereto and the other member comprising a cap piece, a board and a wear plate, the cap 100 piece and wear plate having inwardly extended slots at their ends and flanges projected from one of said parts in line with the sides of said slots and the board having kerfs to receive said flanges, the outer portions of the parts separated by kerfs being adapted to be cut away to receive the standards. 105

4. In a wagon bolster, the combination of a lower member formed with upwardly extended flanges, an upper member comprising pendent side flanges having a telescoping connection with the before mentioned flanges of the lower member, and stakes adjustably mounted upon the lower member and formed with sockets closing the open 115 ends of the bolster.

5. In a vehicle bolster, the combination of a member having side pieces, or flanges, channeled strut pieces fitted within the bolster and adapted to brace the side pieces 120 thereof and bolts for securing the bolster to the running gear and having their heads fitted between the flanges of the channeled struts.

6. A bolster comprising a lower member 125 of substantially U-form in transverse section throughout its length, stakes having closed sockets at their lower ends to receive the end portions of said lower member and close the same and give a finished appearance thereto, 130

an upper member of substantially U-form throughout its length having its sides embracing the sides of the lower member and opposite sides of the stakes, the end portions 5 of the horizontal part notched or cut away to receive the said stakes, springs interposed between the two members and housed and protected thereby, and means for holding

the said upper and lower members together and limiting their relative vertical play. 10

In testimony whereof I affix my signature in presence of two witnesses.

FREDERICK W. BLECKLEY. [L. S.]
